UNITED STATES PATENT OFFICE

2,007,255

FRAME FOR AUTOCARS

Gustav Röhr, Cronberg, Germany

Application April 20, 1932, Serial No. 606,472
In Germany May 15, 1931

8 Claims. (Cl. 296—28)

My invention relates to the frames of autocars and has for its object to improve the connection of the underframe of the car with the posts of the car body.

5 It is already known to interconnect the underframe of an autocar and the frame of the car body in such a manner that a rigid structure is formed, in order to obtain the smallest possible weight and high strength, the girders of the 10 underframe and the posts of the car body having a box-shaped cross section. My invention has reference to structures of this kind and has for its object a connection of the box girders or 15 bearers of the underframe and those forming the posts of the car body, in which no special connecting members such as gusset plates or corner plates are required and, nevertheless, the whole 20 combined frame structure is sufficiently rigid to take up the bending and torsional stresses the 25 structure is exposed to. According to my invention this object is achieved by the inner wall of every post of the car body frame being fixed to the top wall of the respective longitudinal girder of the underframe near the inner edge of the latter, while the outer wall of the posts is fixed to 30 the outer wall of the girder near the lower edge of the latter. This connection between the posts and the longitudinal girders becomes particularly 35 simple, if the longitudinal girders are fitted on their inner upper and lower outer edge with external flanges, as these flanges are very well suited for fixing the inner and outer wall of the 40 posts of the car body frame.

In order that my invention may be clearly 45 understood and readily carried into effect, an embodiment of the same is illustrated by way of example in the accompanying drawing in which

Figure 1 is a perspective fragmentary sectional view of a longitudinal girder of an underframe 50 with a door post of the car body fixed thereto in the manner forming the subject-matter of the invention and

Figure 2 is a similar view of the same parts, seen from outside.

55 Referring to this drawing, 1 denotes one of the longitudinal girders of the underframe of an autocar which girder has box-shaped cross section, and 2 denotes a door post of the car body, likewise of box cross section. The cross section of the door post is quadrangular and gradually enlarges at bottom in the longitudinal and transverse direction of the girder 1. The enlargement of the cross section in transverse direction depends upon the desired curvature of the outer surface 2^a of the door post 2 down to the lower edge

of the outer wall 1^a of the longitudinal girder 1, while the inner wall 2^b of post 2 extends with an adequate inner curvature down to near the inner edge of the top wall 1^c of the girder 1. Both the outer and inner walls 2^a and 2^b of the post 2 terminate by flanges 2^c and 2^d, respectively, by which the post is fixed to the girder 1 by bolting, riveting, soldering, welding or in any other suitable manner. These flanges form together with the flanges 2^e of the lateral walls of post 2, see Figure 2, a continuous bearing and fastening surface round about the lower end of post 2 on the upper and outer wall of the longitudinal girder 1.

In the embodiment illustrated the longitudinal girder 1 is composed of a section iron 3 of Z-shape and a channel iron 4, so that horizontally projecting flanges 5, 6 are formed on the inner upper edge and outer lower edge of the girder. In this way I have suitable surfaces at disposal to which the inner and outer wall of the posts 2 can be fixed very conveniently.

What I claim as my invention is:—

1. In a vehicle body pillar of hollow formation and closed section, an outwardly directed flange at the lower end of said pillar formed by outwardly bending the metal at the margin thereof, said flange continuing in unbroken relation about the periphery of said pillar and lying in planes approximately perpendicular to each other.

2. A vehicle body pillar formed into a box section, the lower end of said pillar having a V-shaped notch formed therein over substantially the complete area of said end with the point of the V located intermediate the inner and outer walls of the pillar, and the metal at the margins of said V being outwardly bent to form securing flanges, said flanges continuing in unbroken relation about the entire periphery of the pillar.

3. In a vehicle body framework, in combination a longitudinally extending rail of box section, a generally vertically extending pillar of box section interfitting an outer corner of said rail with the central axis of the pillar interfitting and extending at an angle to the upper face of said rail, and flanges on the lower end of said pillar fitting complementary surfaces on said rail and secured thereto, said flanges continuing in unbroken relation about the entire periphery of the pillar.

4. In a vehicle body framework, in combination, a longitudinally extending rail of box section, a vertically extending pillar of box section, and upper horizontally and lower vertically extending flanges on both sides of the lower end of said pillar fitting complementary surfaces of said

5 rail and secured thereto, the box section portion of said pillar extending below the plane of said horizontal flanges, said flanges continuing in unbroken relation about the entire periphery of the pillar.

5. In a vehicle body framework, a rail and a pillar both of box section, the lower end of said pillar having its center line disposed at an angle to the top and side faces of the rail and being 10 notched out from its inner edge to its outer edge and a corner of said rail being received therein, and means for securing said rail and pillar together, said securing means comprising an unbroken flange extending entirely about the lower 15 end of said pillar.

6. In a vehicle body framework, a box sectioned rail having flanges at diagonally opposite corners thereof, a pillar of box section having a notch formed in the lower end thereof, an unflanged 20 corner of said rail being received in said notch, and flanges on the lower end of said pillar secured to the flanges aforesaid.

7. In a vehicle body framework, in combination, a box sectioned sheet metal pillar having a 25 notch cut in the lower end thereof in such a manner as to leave a material amount of the side walls

of said pillar below the upper limit of said notch, flanges formed on the lower ends of the inner and outer walls of said pillar, and a sheet metal rail fitting into said notch in said pillar and having flanges complementary to said flanges on said pillar and secured thereto. 5

8. A vehicle body framework including a side rail and a door pillar, both of box section, said rail including a horizontally extending bottom plate, a Z-sectioned member having the foot of 10 the Z in contact with said plate, and a U-sectioned member having a side thereof secured in contact with said plate with the bottom of the U in spaced relation to the leg of the Z and the remaining side of the U in contact with the head 15 of the Z, a box sectioned pillar resting on said rail, a flange on the lower end of said pillar overlapping the head of said Z along the area where the latter contacts with said side of said U, means common to said flange, Z-sectioned member and 20 said U-sectioned member securing them together, a second flange on said pillar overlapping the foot of said Z, and means common to said second flange, said Z-sectioned member and said plate member securing them together. 25

GUSTAV RÖHR.
